UNITED STATES PATENT OFFICE

136,463

DESIGN FOR A TOOTHBRUSH

Reed W. Robinson, San Francisco, Calif.

Application January 11, 1943, Serial No. 109,229

Term of patent 14 years

To all whom it may concern:

Be it known that I, Reed W. Robinson, a citizen of the United States and a resident of the city and county of San Francisco, State of California, have invented a new, original, and ornamental Design for a Toothbrush, of which the following is a specification, reference being had to the accompanying drawing, forming a part thereof.

In the drawing,

Fig. 1 is a back plan view of a tooth brush embodying my new design.

Fig. 2 is a perspective view of a tooth brush showing my new design.

Fig. 3 is a side view of the brush of Fig. 1 as seen from the line 3—3 thereof.

I claim:

The ornamental design for a toothbrush, substantially as shown.

REED W. ROBINSON.
